UNITED STATES PATENT OFFICE.

WALTER P. MURPHY, OF CHICAGO, ILLINOIS.

SHEET-METAL END STRUCTURE FOR RAILWAY-CARS.

1,236,744.

Specification of Letters Patent. Patented Aug. 14, 1917.

Application filed November 25, 1912. Serial No. 733,369.

To all whom it may concern:

Be it known that I, WALTER P. MURPHY, a citizen of the United States, residing at Chicago, in the county of Cook and State 5 of Illinois, have invented certain new and useful Improvements in Sheet-Metal End Structures for Railway-Cars, of which the following is a specification.

My invention relates to a sheet metal wall 10 structure for railway cars, more particularly for the end wall of the car, and the primary object of the invention is to provide a structure of this sort consisting of one or more sheet metal panels having corrugations 15 which run to opposite edges of the panel, this feature facilitating the pressing of the corrugations; and, further, to provide pairs of attaching members for the panel or panels, one pair at each of the edges of the panel to 20 which the corrugations run, between which said edges are arranged and to which they are attached, whereby the corrugations form, in effect, restrained beams, giving the panel great strength and rigidity.

25 The invention is illustrated in certain preferred embodiments in the accompanying drawings, wherein—

Figure 1 is an elevation of the super- 30 structure of a railway box car provided with a corrugated sheet metal end wall constructed in accordance with my invention.

35 Figs. 2 and 3 are views, in perspective, of one pair of attaching members for the panels, Fig. 2 being the outer member and Fig. 3 the inner member, these figures being on a smaller scale than Fig. 1.

Fig. 4 is a sectional plan, on an enlarged scale, on line 4—4 of Fig. 1.

40 Fig. 5 is a vertical sectional view on line 5—5 of Fig. 1.

Fig. 6 is a view corresponding to Fig. 4, illustrating a modification, and

Fig. 7 is a vertical sectional view on line 7—7 of Fig. 6.

45 Like characters of reference designate like parts in the several figures of the drawings.

Referring first to Figs. 1 to 5, inclusive, the end structure consists of an upper corrugated panel 10, a lower corrugated panel 11, and at each side of the car a pair of attaching members 12 (Fig. 3) and 13 (Fig. 2), the members 12, 13 being preferably angular in cross-section. The panels are formed with corrugations 14 which run to 50 the vertical edges of the panels. Preferably, one flange of each of the angular attaching

members 12, 13 is formed with a plurality of short corrugations, the other flange being flat, the corrugated flanges closely fitting the corrugated edges of the panels. The attaching members are secured by means of bolts 15, or other suitable attaching devices, to the corner posts 16 of the car, the bolts 15 extending through the side sheathing 17 of the car, the corrugated flange of member 13 60 lying on the inside of the panels against the corner post, the corresponding flange of member 12 overlapping the edges of the panels on the outside. Panel 10 overlaps panel 11 and is secured thereto by a line of 65 rivets 18. The attaching members have flattened portions 19, 20 so that they fit the panels closely at these places. Preferably the lower panel has an inturned flange 21 which is secured by bolts 22 to the end sill 23 70 of the car, the flange intervening between the end sill and the flooring 24. The upper edge of panel 10 is secured to the end plate 25 by means of bolts 26 which extend through the fascia plate 27. The edges of 75 the panels are secured to the corrugated flanges of the panels by means of rivets 28, 29.

A modification is shown in Figs. 6 and 7. In this construction the corrugated panels, 80 the lower panel 11^a being shown, are secured between pairs of angular corrugated attaching members 12^a, 13^a, the flat flanges of which lie on opposite sides of the corner post 16^a and are secured thereto by bolts 90 15^a. I have also shown a flat sheet steel lining plate 30, the vertical edge of which is secured to the panel and to the attaching members by rivets 28^a. The lining plate may be also secured to panel 11 at the points intermediate the sides of the car by rivets 31. I do not claim the lining plate in this application. The other parts of the car construction shown in Figs. 6 and 7, and not described, are the same as corresponding parts 95 100 in the construction of Figs. 1 to 5, inclusive, and are given corresponding reference numerals.

A car end of either of the constructions above described can be economically manufactured. The pressing of the corrugations is simplified by having the corrugations run to the edges of the sheet. The pressing operation can be carried on in the ordinary corrugating machine. The construction is 105 110 extremely strong and rigid, due to the fact that the corrugations, which function as

beams, are fixed between rigid attaching members, namely, members 12 and 13, or 12^a and 13^a, as the case may be. The corrugations are, in effect, restrained beams and 5 function as such in transmitting to the framing of the car the load of shifting cargoes.

I claim:

1. The combination with a railway car, of 10 an end structure comprising an end sheet formed with corrugations which extend to the edge of said sheet, a pair of attaching members provided with flanges secured to the car body and with corrugated portions 15 between which the corrugated edge of said end sheet is secured.

2. The combination with a railway car, of 20 an end structure comprising an end sheet formed with corrugations which extend to the edge of said sheet and merge one into the other, a pair of angular attaching members provided with flanges secured to the car body and with corrugated portions between 25 which the corrugated edge of said end sheet is secured.

3. The combination with the corner posts 30 of a railway car, of an end structure comprising an end sheet formed with horizontal corrugations extending to the edges of said sheet and merging one into the other, and a pair of attaching members at each side of the car provided with flanges secured to opposite sides of said corner posts and with corrugated portions between which 35 the corrugated edges of said end sheet are secured.

4. The combination with the corner posts 40 of a railway car, of an end structure for the car comprising corrugated sheet metal panels extending across the car from one corner post to the other, and a pair of attaching

members, angular in cross section, secured to each of the corner posts between which the outer edges of said panels are fastened.

5. The combination with the corner posts 45 of a railway car, of an end structure for the car comprising corrugated sheet metal panels extending across the car from one corner post to the other, and a pair of attaching members angular in cross section secured 50 to each of the corner posts on opposite sides thereof between which the outer edges of said panels are fastened.

6. The combination with the corner posts 55 of a railway car, of a corrugated sheet metal end structure for the car having along its vertical edges means providing two pairs of attaching flanges which stand at right angles to the plane of the end and are adapted to overlap and be secured to 60 opposite sides of the corner post in each case.

7. A sheet metal end structure for a railway car, comprising a sheet metal panel extending across the end of the car and formed 65 with corrugations which run to opposite edges of the panel, and pairs of angular attaching members, one pair at each of said edges between which the said edges are fastened.

8. In a railway car, a sheet metal panel 70 having corrugations running to opposite edges thereof, and pairs of attaching members, one pair at each of such edges which overlap the said edges on both sides thereof, to which said edges are fastened so that the corrugations form, in effect, restrained beams.

WALTER P. MURPHY.
